DESIGN FOR A STOPPER TOP

Michael Piluso, Brooklyn, N. Y.

Application November 2, 1938, Serial No. 80,834

Term of patent 14 years

To all whom it may concern:

Be it known that I, Michael Piluso, a citizen of the United States, residing in the Borough of Brooklyn, in the city of New York, in the State of New York, have invented a new, original, and ornamental Design for a Stopper Top, of which the following is a specification, reference being had to the accompanying drawing, forming part thereof.

Fig. 1 is a top plan view of a stopper top embodying my new design;

Fig. 2 is a side elevation thereof;
Fig. 3 is a bottom plan view of the same; and
Fig. 4 is a cross section of the top taken on line 4—4 of Fig. 3.

A characteristic feature of the design is the formation of parallel ridges in the base of the top.

I claim:

The ornamental design for a stopper top, as shown and described.

MICHAEL PILUSO.
